Patented Feb. 27, 1917.

UNITED STATES PATENT OFFICE.

THOMAS O'BRIEN, OF BROOKLYN, NEW YORK.

MACHINE FOR MEASURING AND MARKING SHOE-SOLES.

1,217,208.

Specification of Letters Patent. Patented Feb. 27, 1917.

Application filed March 31, 1913. Serial No. 757,770.

To all whom it may concern:

Be it known that I, THOMAS O'BRIEN, a citizen of the United States, residing at the city of New York, borough of Brooklyn, 5 county of Kings, and State of New York, have invented a certain new and useful Machine for Measuring and Marking Shoe-Soles, of which the following is a specification.

10 This invention is a machine whose purpose is to indicate upon pieces of leather the size of the sole which may be most advantageously and economically cut from each respective piece.

15 Broadly stated, the invention embodies a stamping member provided with a character designating member, which stamping member is actuated for the purpose of printing, stamping, or otherwise designating upon the 20 article, the characters on said stamping member. With this stamping mechanism cooperates a measuring device serving as selecting mechanism whereby the character on the stamping member, which designates the 25 size of the article to be operated upon, is automatically brought into position for marking said article.

In one of its practical embodiments, the 30 invention comprises a table upon which the article to be stamped may be laid, a rotary stamping member positioned for vertical movement with respect thereto, said stamping member embodying a disk having stamping dies on its circumference, means for bringing any one of said stamping dies into 35 engagement with the article to be stamped, measuring mechanism movable toward and away from the stamping member, means for imparting rotary motion to the stamping 40 member by the movement of the measuring device, and means for determining the proper engagement between the stamping member and the article to be marked.

In the accompanying drawings, I have 45 illustrated different practical embodiments of the invention, but the constructions shown therein are to be understood as illustrative, only, and not as defining the limits of the invention.

50 Figure 1 is a side elevation showing a practical embodiment of the shoe stamping machine of the present invention.

Fig. 2 is a plan view thereof.

Fig. 3 is a horizontal section taken on 55 line 3—3 of Fig. 1.

Fig. 4 is a fragmental side elevation of

one end of the machine, certain parts being omitted for the sake of clearness.

Fig. 5 is a longitudinal, vertical section, taken on line 5—5 of Fig. 2, a certain ratchet 60 wheel being shown in full.

Fig. 6 is a transverse vertical section on line 6—6 of Fig. 2.

Fig. 7 is a development of the circumference of the stamping member. 65

A indicates a table which may be suitably supported on a standard A'. At one end of the table is a vertical slideway α , in which a bar b , is mounted for vertical movement. The upper end of the bar b , extends 70 inwardly over the table, and is provided with a bearing B, for horizontal shaft C. Fixed on the forward end of the shaft is a stamping member D, which member is provided with circumferentially disposed characters d , illustrated in the drawings as the numerals 2, 2; 3, 3; etc., up to 11, 11, indicating shoe sizes in full and half sizes, respectively, (see Fig. 7).

At the opposite end of the table from the 80 stamping member D, is positioned a carriage E, mounted for longitudinal movement on the table, between the guides e . This carriage is provided with an upwardly and rearwardly extending arm E' , and to 85 the outer end thereof is pivoted a rack F, which extends longitudinally of the table and into operative engagement with a gear G, fixed on the shaft C. A guard f is secured to the bearing by means of the screws 90 f' , and is operable to retain the rack F against displacement from its coöperating gear G. It is manifest that movement of the carriage will be transmitted to the shaft 95 C, to rotate the stamping member D. Moreover, to aid in the movement and further operation of said carriage, it is normally impelled in the direction of the stamping member by a spring I, secured to the table by bolt i , and to the carriage by a bolt i' , 100 which works in slot a' in the table.

A gage H, provided with a cam surface, is pivotally mounted on the table A by a screw h , said gage being in substantial alinement with carriage E. Said gage is provided with an elongated arm H' , which arm is acted upon by a spring h' , whereby the gage is normally retained to present the high point of its cam toward the path of movement of the carriage. 105

At the lower end of bar b , which carries bearing B for shaft C, a treadle or 110

stirrup J is secured by the screw j, which treadle is retained in proper alinement with said bar by a bracket j' mounted on standard A'. A spring K is secured at one end to the table and, at its opposite end, to the treadle, and said spring is under sufficient tension to normally lift bar b, and the parts mounted thereon, until the stop b' engages the edge of the guideway a (see Fig. 1).

10 The operation of the machine described is as follows:—

With the stamping member in its normally raised position, shown in Fig. 1, the piece of leather to be measured and marked 15 is placed on table A, against the rounded, forward end of carriage E, and, as said carriage is pushed back, against the tension of spring I, the leather is moved into alinement therewith and properly positioned with relation thereto, by the aid of stops L, L, which may be inserted in any two of a series of holes l in the table. The operator now releases the leather, and immediately 20 the tension of the spring I moves the carriage forward, until the forward edge of the leather engages the high point of the cam surface on gage H, the leather being outlined in Fig. 1 in dot and dash lines. Furthermore, the carriage in its forward 25 movement operates the rack and pinion F and G, respectively, thereby causing the member D to be rotated, for the purpose of bringing the proper numeral d into position for marking the leather.

30 As hereinbefore stated, the disk and carriage operate in unison, *i. e.*, their relative movement is such that when the carriage moves toward the marking member for a distance corresponding to a shoe size, the 35 marking member will be rotated coextensive therewith. For example, there is approximately $\frac{1}{3}$ of an inch difference in length between two successive sizes of shoes. Now, if the carriage is in a position wherein the 40 distance between the forward end thereof and the gage H is equal to a size 10 shoe, and the member D is positioned so that the disk stamp d, bearing character "10" will be in proper position for stamping, and from 45 this position the carriage is moved forward $\frac{1}{3}$ of an inch, the rack will operate shaft C to revolve the stamping member to such extent that the disk stamp d, which bears the character "9" will be in proper stamping position. If, however, the carriage is moved but $\frac{1}{6}$ of an inch, the marking member will 50 revolve but one-half as far and the character "10" (ten and one-half) will be brought into stamping position.

55 When the parts are thus positioned, it is only necessary for the operator to apply downward pressure on the treadle J, which pressure will overcome the tension of spring K, and cause member D, which is carried by 60 the vertically movable bar b, to be brought

into engagement with, and forcibly pressed upon, the surface of the leather, whereby the proper character d, on the circumference of said member will be impressed into, and consequently mark, said leather.

In practice, it is very seldom, however, that a piece of leather is of a length equal to any exact size or half size, but frequently varies slightly therefrom, *e. g.*, the piece may be equal in length to approximately size 75 $10\frac{1}{2}$. Obviously, from the foregoing description, a piece of this size would not properly position for stamping any of the characters d on the member D, and, if the treadle were operated, the adjacent edges of 80 both the characters designated "10" and "10," would engage the leather, leaving no intelligible mark thereon. This difficulty is obviated by the cam-shaped edge H, which may be operated to compensate for such 85 slight variations in lengths. In the present instance of the $10\frac{1}{2}$ length, the operator adjusts the arm H' of the gage in the direction indicated by the arrow in Fig. 3, and to such an extent that the carriage pushes forward with the leather sufficiently to revolve member D into a position wherein the character d, bearing the designation "10," will 90 properly stamp the leather. Thus, said piece of leather will be marked size "10," it 95 being too short for a size "10" (ten and one-half).

In operation the machine, thus far described, the aforesaid variation in sizes 100 makes it necessary for the operator to carefully watch the marking member, in order that the cam-shaped gage will be operated to preclude the striking of the die when the members d, thereon are not properly positioned, and this is facilitated to some extent, by beveling the face of member D, as at d', and placing thereon characters corresponding to the characters d. Moreover, a finger or pointer M is mounted on bearing B, and reaches over the circumference of the member into close proximity to the characters on beveled portion d'. The last mentioned characters are so disposed relative to the characters d, that the pointer M indicates the character which is in proper stamping 105 relation to the leather and further indicates to the operator when none of the characters d are in such position.

The machine, as thus far described, requires a certain manual adjustment of the gage, but it is desirable to provide a machine which will be automatic in its operation. I have illustrated in the drawings, and will now proceed to describe, means 110 which may be employed with said machine, for the purpose of automatically compensating for variation in the length of the pieces to be marked.

A ratchet wheel N (Fig. 5) is fixed to 115 shaft C, which carries member D, and said 120

wheel has a number of notches n , in its circumference, equal to the number of characters d on member D.

A bushing O is tapped into an orifice in table A, situated in the vertical plane of the axis of the shaft C, and directly beneath the wheel N. This bushing is open at its bottom, and its top is closed, except for a square hole, through which is adapted to pass a correspondingly shaped pawl P. A spring o, presses against the lower end of said pawl for normally pressing it through the opening in the top of the bushing as far as the collar p' on the base of said pawl will permit.

The top end of the pawl P, is beveled, as at p, to correspond in shape to the notches n , in the wheel N, which are so formed that but one side of each notch is radially disposed with respect to the wheel. It will be manifest, from Fig. 5, that, if bar b is lowered, i. e., when the shaft C and stamping member D are brought down to stamp a piece of leather, so that the upper beveled end of pawl P engages a notch in the circumference of the wheel, said pawl will engage the side of one notch and cause said wheel to turn while it is being lowered with the bar and the marking mechanism, at the end of its downward travel, the point of the pawl engages the base of said notch. During this operation, the spring I, beneath the pawl, will form a cushion and ease the shock or jar. Obviously, therefore, if the stamping member D, and the wheel N, are so initially positioned that a character d , on the circumference of the former, is in proper stamping position when the point of the pawl P is in engagement with the base of a notch in the circumference of the member D, the pawl and wheel will coöperate to insure the proper positioning of the characters d , during the operation of the machine.

Furthermore, the fact that the notches in said wheel are formed by radial and beveled sides will cause any required shifting of the wheel to be in the direction which will shift the marking member to mark the next lower character.

When this automatic mechanism is employed, it operates in conjunction with the gage H, for the reason that, when the star-wheel is turned to bring the stamping member into proper position, the gear G, on shaft C, is also rotated, thereby drawing the carriage E forward. This forward pull, coupled with the tension on the spring I, is just sufficient to overcome the comparatively slight tension on spring h', which operates the gage H, to cause said gage to swing on its pivot h, and thus allow the leather to advance a trifle, i. e., just enough for the proper positioning of the stamping member.

It will thus be seen that operation of marking the pieces consists in backing off

the carriage and placing the piece of leather against the stop-pins, after which the spring-impelled carriage advances and carries the leather with it into the substantially correct position for marking. Then, by a downward pressure on the treadle, the coöperating pawl and ratchet act to place the stamping member in proper position and immediately thereafter mark the sole.

In its preferable embodiment, the machine is provided with the coöperating pawl and ratchet means which serves to mechanically adjust said mechanism to slight variations in sizes of the leather blanks to be marked. It will be obvious, however, that, if desired, the pawl and ratchet mechanism may be entirely dispensed with, and the gage H manually operated in the manner hereinbefore set forth to properly position the sole to be stamped.

Moreover, certain details of construction may be modified, from time to time, and the specific structure of the stamping member, herein set forth, may also be changed or modified, without departing from the spirit and scope of my invention. For these reasons, I do not wish to be understood as limiting myself any further than the state of the art may require.

Having thus fully described the invention, what I claim as new, and desire to secure by Letters Patent is:—

1. In a sole marking machine, the combination with sole-supporting means, of a rotatable marking head mounted for reciprocating movement relatively to said sole-supporting means, said marking head being provided with a series of characters for impressing upon different soles markings for denoting the lineal dimensions of said soles, a measuring device positioned for contact with the sole, said measuring device embodying two members one of which is movable freely with respect to the other member, means connecting said freely movable member with the marking head for imparting variable rotative movement to the latter, and means independent of the head-rotating means for imparting reciprocating movement to the marking head with respect to the sole supporting devices.

2. In a sole marking machine, the combination with a sole support, of a rotary marking head mounted for reciprocating movement relatively to the sole support, said marking head being provided with a series of characters for impressing upon different soles markings denoting the lineal dimensions thereof, a measuring device the operation of which is dependent upon the length of the sole adapted to be positioned upon the sole support, means controllable by the movement of the measuring device whereby variable rotative movement is imparted to the marking head, and means operable at

will for imparting to the marking head a reciprocating movement with respect to said sole support, said head reciprocating means being independent of the operation of the 5 head-rotating means.

3. In a sole marking machine, the combination with a sole support, of a measuring device embodying a slidable member and a manually controlled gage between which 10 the sole to be measured is adapted to be positioned, said gage being shiftable at will for presenting different portions of its working face in the path of said slidable member, a marking head, means operable by 15 the movement of the slidable member for shifting the marking head into different positions for marking shoe soles according to their sizes, and means for imparting reciprocating movement to said marking head 20 relatively to the sole support.

4. In a sole marking machine, the combination with a sole support, of a sole measuring device embodying a slidable member and a relatively fixed gage positioned in the 25 path of the slidable member and co-operating therewith in determining the length of a sole adapted to be positioned upon the sole support, a marking head, means operated by the movement of the slidable member 30 for shifting the position of said marking head, and means for effecting a relative movement between the sole support and the marking head, said relatively fixed gage being provided with a cam-shaped face and 35 said gage being shiftable at will to vary the position of said cam-shaped face with respect to the slidable member.

5. In a sole marking machine, a sole measuring device embodying a slide and a gage 40 member separate from the slide and positioned in the path of said slide for measuring the length of a sole, said gage member being shiftable at will to different operative positions with respect to the slide, in combination with a rotatable marking head, means 45 controlled by the movement of the slide for imparting rotative movement to the marking head, a sole support, and means for effecting a relative movement between the 50 sole support and the marking head.

6. In a sole marking machine, the combination of a marking member, a sole support,

means for effecting a relative movement between the marking member and the sole support, a measuring mechanism including two 55 parts one of which is movable relative to the other, means operated by the movement of one member of said measuring mechanism for shifting the marking member to different predetermined positions, and means separate from the measuring mechanism for automatically shifting the marking member for fractional distances corresponding to a slight variation in the sizes of the soles to be operated upon. 65

7. In a sole marking machine, the combination of a sole support, a marking member, means for effecting a relative movement between the sole support and the marking member, a measuring mechanism, means operated by the measuring mechanism for shifting the marking member to various predetermined positions, and automatic shifting means embodying a pawl and ratchet operable to change the position of the marking member for fractional distances between the predetermined shift so as to correspond to slight variation in the length of the soles. 75

8. In a sole marking machine, the combination of a sole support, a rotatable marking head, a reciprocating carrier for presenting the same to the sole to be operated upon, a measuring device dependent for its operation upon the linear dimensions of the 85 sole to be marked, means controlled by the marking mechanism for shifting the marking head to various positions corresponding to the linear measurement of the material as determined by the measuring device, and 90 means separate from the marking mechanism and operated by the movement of the marking head for imparting rotative movement to said marking head for fractional distances corresponding to a slight variation in the sizes of the soles to be measured. 95

In testimony whereof I have signed my name to this specification in the presence of two subscribing witnesses.

THOMAS O'BRIEN.
